UNITED STATES PATENT OFFICE.

LEWIS L. HEPBURN, OF NEW HAVEN, CONNECTICUT, ASSIGNEE TO THE MARLIN FIRE ARMS COMPANY, OF SAME PLACE.

SAFETY LOCKING DEVICE RELEASED BY RECOIL.

SPECIFICATION forming part of Letters Patent No. 662,427, dated November 27, 1900.

Application filed June 14, 1900. Serial No. 20,272. (No model.)

To all whom it may concern:

Be it known that I, LEWIS L. HEPBURN, a citizen of the United States, residing at New Haven, New Haven county, Connecticut, have 5 invented certain new and useful Improvements in Breech-Loading Firearms, of which the following is a full, clear, and exact description.

My invention relates to improvements in 10 breech-loading firearms, and particularly such arms as shotguns, rifles, and the like of the repeating type.

The chief object of the invention is to provide a supplemental safety locking device 15 which will prevent accidents resulting from the premature unlocking or opening of the breech in case the cartridge "hangs fire."

My invention is illustrated in the accompanying drawings, in which—

20 Figure 1 is a side elevation, partly in section, of the breech portion of the repeating firearm provided with my improved safety device, the breech being closed. Fig. 2 is a similar view of the same parts that are shown in Fig. 1, the breech being open. Figs. 3, 4, 5, 6, 7, and 8 are views of detached details of construction.

25 In the particular embodiment shown in the drawings, 1 is a frame, and 2 is a breech-block adapted to move therein.

30 3 is a locking-bolt carried by the breech-block and adapted to tilt therein, so that when in the position shown in Fig. 1 its forward end bears firmly against a wall at the 35 forward inner end of the breech-block and its rear end bears solidly against an abutment in the frame. In this position the parts are locked ready for firing. In Fig. 2 the locking-bolt is shown as tilted to a horizontal position, in which its rear end is freed from the frame, so that the breech-block may be retracted and the breech opened.

35 4 is a tilting cartridge-carrier which is pivoted at one end and works up and down in a 40 manner suitable to convey the cartridges successively from the magazine 5 up into the position directly to the rear of the barrel 6, so that by the forward or advance movement of the breech-block 2 the loaded cartridge 45 may be inserted into said barrel in a position 50 ready for firing.

7 is a movable operating-rod manually controlled and by which the breech-operating mechanism is actuated. This rod 7 carries a stud 8 near its rear end, which engages with 55 a shoulder 9, depending from the locking-bolt 3. This stud 8 engages the shoulder 9 in a cam-groove in the side thereof, so that by the movement of the rod 7 and stud 8 the locking-bolt 3 may be tilted into either the 60 position indicated in Fig. 1 or in Fig. 2.

10 is a stud on the side of the depending shoulder 9, which stud projects into a cam-groove in the side of the carrier 4, so that by the movement of the shoulder 9 the carrier 4 65 is raised or lowered.

11 is a hammer which may be controlled by the usual trigger 12.

13 is a firing-pin carried by the breech-block and against which the hammer is adapted to strike and by which a cartridge may be exploded in the usual manner.

70 The purpose of the invention herein is to prevent the premature opening of the breech mechanism before the cartridge in the barrel shall have exploded. This end is accomplished by the employment of a supplemental locking device 14, which is suitably pivoted to the frame, so that it may tilt or swing. This locking device 14 is preferably provided 75 with spring 15, which causes it to normally swing in a rearward direction.

16 is a hook at the upper end of the locking device 14, which hook is adapted when said locking-bolt is in the position shown in Fig. 85 1 to engage with a shoulder 17, suitably formed upon the locking-bolt 3. This hook 16 may have its upper side inclined or beveled, so that when the locking-bolt is tilted from the horizontal position into the inclined position 90 the shoulder 17 will momentarily push said locking device 14 slightly forward, forcing its way past the hook, at which instant said device 14 will spring back and hook over the shoulder 17, as shown in Fig. 1, wherein it 95 will prevent the tilting of the locking-bolt 3 until it is freed therefrom by the tripping of the locking device 14. Inasmuch as the bulk of the weight of said locking device 14 is above the pivotal connection therefor the recoil occasioned by the explosion of a cartridge 100 will cause, by inertia, the locking device 14

to swing forward, freeing the hook 16 from the shoulder 17. The locking device 14 may be held in this forward position by a suitable latch 18, which may engage the front of a nose 19, carried by a part of the breech mechanism—for example, the carrier 4. In the particular form shown the latch 18 has a bevel nose and is in the form of a spring-pressed piston, although other forms might obviously be substituted. The forward position of the locking device 14 is shown in dotted lines in Fig. 1. When this part 14 is in the position shown in dotted lines, and the other parts are in the position indicated in Fig. 1, the breech mechanism may be freely operated. The operation of the breech mechanism will cause the carrier 4 to be depressed or lowered from the position shown in Fig. 1 to the position shown in Fig. 2, and the lowering of the same will carry down the nose 19 until it becomes freed from the spring-latch 18, at which instant the locking device 14 may resume its normal retracted position, as shown in Figs. 1, 2, and 8. The continued movement of the breech mechanism will again raise the carrier 4 and effect the introduction of a new cartridge into the barrel, and as soon as the locking-bolt 3 is tilted to lock the breech mechanism ready for firing it will itself become again engaged by the safety locking device 14 in the manner before described. In order to permit the operating of the breech mechanism in case the cartridge in the barrel does not explode or for any other reason, a manually-controlled device may be employed whereby the user may trip or shift the position of the supplemental locking device 14 to its forward disengaged position. In the drawings I have shown such a device in the form of a plunger 20, which slides in the frame adjacent the thumb of the trigger-hand and which projects inside of the casing and against a portion of the locking device 14, so that by pushing this plunger 20 inwardly the locking device 14 may be tilted so as to free the locking-bolt 3, and the breech may then be opened in the usual manner. The locking device 14 may have stops 21 and 22 to limit the tilting movement of the same.

I have found from practical use that this improvement is thoroughly reliable and that it is equally effective whether a light or heavy charge of powder is used in the cartridge. The fact that it is automatically set prevents the danger of accidents, because it relieves the user of that responsibility. By engaging directly with the main locking-bolt of the gun the reliability of the safety device is much greater than it would be if it engaged with some other part or with the locking device through intermediate pieces. Manifestly the construction and operation of the parts herein described are susceptible of modification, and while I have shown one particular and preferable form of firearm in which the safety device may be employed it is obvious that it

may also be applied to other forms of firearms of the repeating type.

What I claim is—

1. In a firearm in combination, a frame, a breech-block, a locking-bolt therefor, an inertia-piece carried by the frame interlocking with said locking-bolt and disengaged therefrom by the recoil of the gun, a carrier, and means on the carrier for retaining the inertia-piece after recoil. 70

2. In a firearm in combination, a frame, a breech-block, a locking-bolt therefor, an inertia-piece carried by the frame interlocking with said locking-bolt and disengaged therefrom by the recoil of the gun, a carrier, means on the carrier for retaining the inertia-piece after recoil, and means for returning said inertia-piece into engagement with the locking-bolt. 80

3. In a firearm in combination, a frame, a breech-block, a locking-bolt therefor, an inertia-piece pivotally supported on the frame, a hook at the upper end thereof, a shoulder on the locking-bolt engaged thereby, a carrier, and means on the carrier for temporarily retaining the inertia-piece after recoil. 90

4. In a firearm in combination, a frame, a breech-block, a locking-bolt therefor, an inertia-piece carried by the frame and interlocking with said locking-bolt and disengaged therefrom by the recoil of the gun, a carrier, and means for temporarily engaging the inertia-piece with the carrier after recoil, said means comprising shoulders upon each of said parts, one of said shoulders being yielding and spring-controlled. 95

5. In a firearm in combination, a frame, a breech-block, a locking-bolt therefor, an inertia-piece carried by the frame and interlocking with said locking-bolt and disengaged therefrom by the recoil of the gun, a carrier, a spring-pressed stud on the inertia-piece and a shoulder on the carrier over which the stud passes upon the recoil of the gun and by which the inertia-piece is held against return engagement with the locking-bolt until released by the movement of the carrier. 105

6. In a firearm, in combination, a frame, a breech-block movable therein, a locking-bolt associated with said breech-block and movable therein, means for actuating said parts, a cartridge-carrier coacting with said locking-bolt, a supplemental locking device in the form of an inertia-piece carried by the frame and normally in engagement with the locking-bolt, said supplemental locking device being displaced by the recoil of the gun, and means carried by the carrier for temporarily holding said supplemental locking device in its disengaged position and automatically releasing the same at each operation of the breech mechanism. 115
